(57) **CLAIM**

The ornamental design for a handheld terminal, as shown and described.

DESCRIPTION

FIG. 1 is a top front perspective view of a handheld terminal showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof shown in an environment wherein the front area of the handheld terminal is shown wrapped by an unclaimed cover case; and,

FIG. 9 is another perspective view thereof shown in an environment wherein the front area of the handheld terminal is shown wrapped by an unclaimed cover case.

The dot dash broken lines showing the cover case in the FIG. 8 and FIG. 9 views are directed to environment and are for illustrative purposes only; the broken lines form no part of the claimed design.

1 Claim, 7 Drawing Sheets
